UNITED STATES PATENT OFFICE

2,509,679

FLUID FUEL CONTROL DEVICE FOR
MULTIPLE BURNERS

Vincent J. Evans, Lakewood, Ohio, assignor to
Grand Industries, Inc., Cleveland, Ohio, a corporation of Ohio

Application January 11, 1946, Serial No. 640,561

2 Claims. (Cl. 236—15)

1

This invention relates to a fluid fuel control device and particularly to a device for controlling the flow of fuel to a plurality of burners.

One of the principal objects of the present invention is to provide a fluid fuel control device for a plurality of burners in which a single thermostatically operated valve controls the flow of fuel to all of said burners.

Another object is to provide a fluid fuel control device for a plurality of burners and which operates for admitting fuel successively to the burners as the device is operated and in which a single thermostatically operated valve controls the flow of fuel to all of the burners after fuel has been admitted to the last burner.

A more specific object is to provide a low heat burner and high heat burner controlled by a single stop cock and thermostatic valve combination such that, upon rotation of the stop cock in the opening direction, fuel is admitted first to the low heat burner, and then to the high heat burner for effecting concurrent operation thereof with the low heat burner, and a single thermostatic valve is set by the rotation of the stop cock in the opening direction and thereafter controls the operation of both burners.

Another specific operation is to provide a stop cock and thermostatic valve combination for the purposes described which is compact and simple in construction and adapted for use in gas ranges and heaters such as are generally available on the market.

Another object is to provide an oven with a burner and burner control by which efficient heat control in the oven is obtained.

Another object is to provide a multiple burner and control combination by which the proper cooperative relation of the burners is effected by the setting of a single rotatable dial.

Other objects and advantages will become apparent from the following description wherein reference is made to the drawings, in which

Fig. 1 is a schematic view of a control and burner combination embodying the principles of the present invention, the control device and a portion of the burner being shown in section for clearness in illustration;

Figs. 2 and 3 are cross sectional views taken on the lines 2—2 and 3—3, respectively, of Fig. 1;

Fig. 4 is a fragmentary side elevation of an oven with the control and burner combination installed therein, the fragment of the oven being shown in section.

For the purposes of illustration, the present invention is shown for controlling the supply of

2

gaseous fuel to a dual burner for an oven of a cooking range, its use in connection with a single burner or a plurality of separate burners employing gas or other types of fluid fuel, and for heating other compartments, being readily apparent from the illustrative example.

As illustrated in the drawings, the dual burner to which fuel is to be supplied under control is shown as comprising a low heat burner 1 having a mixing bell 2 and a high heat burner 3 having a mixing bell 4. In the form illustrated, the dual burner is cast as a single piece, a suitable partition wall 5 segregating the two burners from each other internally. Gas is supplied to the burner 1 through the usual throttling injection nozzles 6 and to the burner 3 through the throttling injection nozzle 7, the orifices 6 and 7 preferably being of the needle valve control type.

Gas is supplied to the orifices 6 and 7 through 20 the local supply lines 8 and 9, respectively, and a suitable pilot burner 10, which is supplied through a local line 11, is provided. The line 11 may be connected to a main line and operate continuously, but is shown connected to the line 8 at 25 some convenient location so that gas is introduced to the pilot 10 for lighting when gas is admitted to the low heat burner 1. Gas is supplied to the burners from a common main supply line 12 connected to a suitable source of gas under pressure.

Interposed between the main line 12 and the local lines 8 and 9 is a control device indicated generally at 13. The control device comprises a hollow body 14 having a connection 15 connecting it to the supply line 12. Within the body 14 is a sleeve 16 which is open at one end to admit gas from the interior of the body into the interior of the sleeve. Rotatably mounted within the sleeve 16 is a stop cock plug 17, the plug 17 being fitted into the sleeve in sealing relation and held in place for rotation about its axis by a suitable spring 18 and cooperating cap 20.

The plug 17 has an axial bore 21 and radial ports 22 and 23 connected therewith and opening, at their outer ends, through the face of the plug 17. The body 14 is provided with complementary ports 24 and 25 which are positioned for registry with the ports 22 and 23 upon rotation of the plug 17 to an open position, and are connected to the lines 9 and 8, respectively. The sleeve 16 also is provided with by-pass ducts 26 and 27 which are controlled by adjustable needle valves 28 and 29, respectively, which are accessible for adjustment from the outside of the body and when opened admit fuel from the interior of the

body through the by-pass ducts 26 and 27, respectively. The plug 17 also is provided with a pair of circumferential grooves 30 and 31, the groove 30 communicating with the port 22 and the groove 31 communicating with the port 23. The grooves 30 and 31 are positioned axially of the plug so that the groove 30 can connect the by-pass duct 26 with the port 24 of the body when the plug is rotated to certain positions and the duct 31 is positioned axially of the plug so as to connect the by-pass duct 27 with the port 25 of the body in certain rotated positions of the plug.

In the heating of an oven, of a gas stove for example, it is desirable, in order to have efficient burner operation, that a dual burner be provided in which the small burner can operate at or near capacity until sufficient heat is required so that the gas to be supplied will be adequate in amount to permit efficient operation of the larger burner. This is particularly true when initially starting the oven and before it has become heated. Accordingly, the groove 31 is made sufficiently longer than the groove 30 and has its leading end in the direction of rotation positioned in advance of the leading end of the groove 30 a sufficient distance so that upon rotation of the plug from a closed position, illustrated in Fig. 1, by-passed gas is first introduced to the burner 1 from the duct 27 and, upon rotation of the plug in the opening direction farther, by-pass gas is introduced to the burner 3 from the by-pass duct 26. The grooves 30 and 31 are sufficiently long so that at all times after the leading ends in the opening direction of rotation of the grooves 30 and 31 have reached their points of communication with the ports 24 and 25, respectively, the by-pass gas is continuously supplied to the burners. This supply is discontinued only by rotating the plug to its off position illustrated in Fig. 1 in which neither of the grooves 30 and 31 and neither of the ports 22 and 23 are in registry with the ports 24 and 25, respectively. Thus the plug is operable and rotated from a closed to an open position first to admit a controlled and adjusted amount of gas to the burner 1 by way of the by-pass duct 27 and then upon further rotation to admit gas to the burner 3 by way of the by-pass duct 26, thereafter continuing the introduction of limited amounts of gas to the burners through the respective by-passes until the plug is rotated in the opposite direction to closed position.

The main supply of gas to the burners is provided through the sleeve 16 and bore 21 of the stop cock. As illustrated, the sleeve 16 is open at the end opposite from the plug 17 and is provided with an annular seat 32. A suitable thermostatically controlled valve plug 33 cooperates with the seat 32 for admitting and stopping the flow of gas from the interior of the body through the interior of the sleeve and bore 21 of the stop cock. The valve 33 is normally held in seated condition by a spring 34, one end of which is seated against the plug and the other end of which is seated against the movable end of a thermostatic bellows 35. The bellows 35, in turn, is connected by a pipe 36 to the usual sealed expandible fluid vial 37 which, in response to heat, operates the bellows.

At the opposite side of the plug 33, an adjusting rod 38 is provided, the adjusting rod being mounted in a suitable spider 39 in and coaxial with the sleeve 16 and plug 17. The adjusting rod 38 is provided with a suitable ball end 40 which is snap fitted into a socket 41 in the valve

plug 33. The rod 38 is preferably of non-circular cross section and is supported by the spider 39 for movement axially and is constrained by the spider from rotational movement. At the opposite side of the spider from the ball 41, the rod 38 is mounted for axial, but non-rotative movement, in a sleeve 43 and a suitable spring 43 is interposed between the end of the sleeve 42 opposite from the rod 38 and the end of the rod so as to urge the sleeve and rod relatively apart axially.

The plug 17 carries a rod 44 which is coaxial and rotatable with the plug and rotatable relative to the sleeve 42 and in threaded engagement with the sleeve 42, as indicated at 45. The plug 17 also is provided at the end opposite the sleeve 42 with a stem 46 which is rotatable with the plug. A suitable knob 47 which has temperature indicia 48 about its periphery is fixedly secured to the end of the stem 46. Thus upon rotation of the knob 47, the stop cock plug 17 is rotated and, the sleeve 42 being constrained from rotation with the rod 44 of the plug, travels along the thread at 45. The thread 45 is so arranged that upon rotation of the plug 17 toward open position, the sleeve is moved axially away from the stop cock and in a direction to compress the spring 43, thus applying to the plug 33 an unseating pressure in opposition to the seating pressure of the spring 34.

In Fig. 1 the plugs 17 and 33 are shown in closed position. In operation the spring 34 sufficiently overbalances the spring 43 so as to maintain the plug 33 in seated condition when the valve plug 17 is in closed position and to maintain it in seated position so that only the bypasses are effective for supplying gas when the plug 17 is rotated for initially supplying gas to the low heat burner and thence initially to the high heat burners. Continued rotation of the plug 17 in the opening direction after by-pass gas has been admitted to both burners, applies sufficient compression on the spring 43 to overbalance the spring 34 and unseat the plug 33 after which time the burners are under the control of the thermostat. Additional rotation of the plug 17 in the opening direction increases the compression of the spring 43 and creates a greater overbalance so that a higher temperature and expansion of the bellows is required to seat the plug 33 and limit the heat to the maximum heat set on the dial 48.

Thus in operation starting from the closed position of the plug 17, an adjusted amount of gas is admitted to the low heat burner 1, the amount being sufficient to maintain efficient combustion by a burner, the burner heating capacity being inadequate to cause high temperature in the oven. Additional rotation of the plug 17 in the opening direction admits an adjusted amount of by-pass gas to the high burner 3, this amount being sufficient to maintain efficient combustion but insufficient to cause heats in the oven above what would be considered a normal low cooking heat. Additional rotation of the plug 17 next opens the thermostatically controlled valve plug 33, admitting gas in addition to that supplied by the by-passes. If the plug is rotated still farther, the unseating pressure is increased so that still higher temperatures must be reached before the plug 33 is closed by the bellows 35. Thereafter any higher range of temperatures is controlled by the thermostat. Thus by rotation of a single knob 47, the admission of gas to the burner for maintaining efficient combustion at various controlled temperatures is

provided and a single thermostatic valve controls the temperature of a plurality of burners.

Referring next to Fig. 4, the device is shown installed on an oven 49 of a gas range, the oven having the usual air inlet and exhaust vents, not shown, and the dual burner being mounted in the oven in the usual fashion. The expansible fluid vial is located in the upper portion of the oven. In such an installation, the control device 13 may be mounted behind the usual front panel of the stove or in any other readily accessible place.

While the device has been shown as employing a bellows type expansible fluid thermostatic control, bi-metallic and other types of thermostats may be used.

I claim:

1. A burner and control combination for gas range ovens comprising a small oven heating burner adapted upon supplying a predetermined flow of fuel thereto to provide low heat in the oven at or near the rated efficiency of the burner, a large burner adapted upon supplying a predetermined partial flow of fuel thereto to provide normal low cooking temperatures in the oven near the rated efficiency of the burner and upon supplying a predetermined larger amount of fuel thereto to provide high cooking heats in the oven at or near the rated efficiency of the larger burner, a valve body adapted for connection to a source of gas and connected to each of the burners, a rotatable plug in the body for admitting and stopping the flow of fuel from the source to the burners, cooperative by-pass means in the plug and body for by-passing fuel to the burners, respectively, said by-pass means being rendered operative upon rotation of the plug from closed toward open position, but in advance of the open position, first to by-pass fuel to the smaller burner

at said predetermined flow and then to by-pass fuel to the larger burner at said predetermined partial flow, a single normally closed adjustable thermostatic valve for admitting fuel to the burners and operable to connect the burners to the source of fuel independently of the by-pass means when the thermostatic valve is open, said thermostatic valve being operable accurately only in the range of high cooking heats above that supplied by the larger burner when the larger burner is operating on said predetermined partial flow, said by-pass means continuing to be operative concurrently with the operation of said thermostatic valve means, and means operatively connecting said thermostatic valve and plug for unseating and adjusting the thermostatic valve in the said range of high cooking heats upon rotation of the plug toward open position beyond the position in which the by-pass means to the larger burner becomes operative to admit fuel to the larger burner.

5 2. The combination according to claim 1 further characterized in that said by-pass means continues to by-pass fuel to the small burner 10 while the plug is in position to by-pass fuel to the 15 larger burner.
